Primary Examiner — L. A. Grabenstetter

(57) **CLAIM**

The ornamental design for a phone cage, as shown and described.

DESCRIPTION

FIG. 1 is a front, left and top perspective view of a phone cage showing our new design;

FIG. 2 is a rear, right and bottom perspective view thereof;

FIG. 3 is a rear view thereof;

FIG. 4 is a front view thereof;

FIG. 5 is a right view thereof;

FIG. 6 is a left view thereof;

FIG. 7 is a top view thereof;

FIG. 8 is a bottom view thereof;

FIG. 9 is a partial enlarged view of a portion labeled as 9 on FIG. 1; and,

FIG. 10 is a partial enlarged view of a portion labeled as 10 on FIG. 1.

The dash-dash broken lines represent features of the phone cage that form no part of the claimed design. The dot-dash broken lines and circles are included for the purpose of disclosing the partial enlarged views and form no part of the claimed design.

1 Claim, 10 Drawing Sheets
